L. A. PETERSEN,
SILo STAGING,
FILED APR. 7, 1922.

INVENTOR:
L. A. Petersen,
Victor J. Evans
ATTORNEY

UNITED STATES PATENT OFFICE.

LAURENCE A. PETERSEN, OF HANNA, WYOMING.

SILO STAGING.

Application filed April 7, 1922. Serial No. 550,555.

To all whom it may concern:

Be it known that I, LAURENCE A. PETERSEN, a citizen of the United States, residing at Hanna, in the county of Carbon and State 5 of Wyoming, have invented new and useful Improvements in Silo Staging, of which the following is a specification.

This invention relates to improvements in silo staging and has particular reference 10 to a staging adapted to be used during the construction of a silo.

The principal object of this invention is to produce a staging which may be employed in the erection of silos of different height 15 and diameter.

Another object is to produce a staging which is extremely simple and one which may be erected by one man and without undue effort.

20 Another object is to produce a silo staging which may be conveniently transported from one place to another the same taking up but a minimum amount of space during transportation.

25 Other objects and advantages will be apparent during the course of the following description.

In the accompanying drawings forming a part of this specification, and in which like 30 numerals are employed to designate like parts throughout the same,

Figure I is a side elevation of my staging, Figure II is a top plan view on the line 35 II—II of Figure I,

Figure III is a detail view of one of the spacer members,

Figure IV is a detail perspective view of a staging plank,

Figure V is a detail perspective view of 40 one of the supporting members.

Figure VI is a fragmentary perspective view showing how the staging is assembled.

In the construction of a silo, it is generally necessary to construct a wooden staging both 45 inside and outside of the silo, the same being made out of rough lumber which is useless after the construction work has been completed, and is knocked down and destroyed. I propose to overcome this waste by employing 50 a staging which may be built up as needed and one which will fit all sizes of silos. I accomplish this object by employing staging built up of units.

In the accompanying drawings wherein

for the purpose of illustration is shown a 55 preferred embodiment of my invention, the numerals 6, 7, 8 and 9 refer to upright supports preferably made of angle iron. These supports are shown in Figures I, II and V. The supports each rest upon the ground and 60 are provided with base plates as shown at 11 and 12, and are formed at their upper ends with slots 13 and 14 as shown in Figure V. These uprights are secured one to the other as by cross braces 16 and 17, it being 65 understood that there are two of these braces extending between each of the four uprights. The construction of these braces is best shown in Figure I where it will be noted that the same are each of laminated construction 70 which allows them to be lengthened by removing fastening bolts 18 and 19 and replacing them in proper openings to provide for the expansion or contraction as desired. Tie members capable of longitudinal 75 adjustment by being formed of two pieces in overlapping relation as clearly shown in Figure III are indicated by the numerals 21, 22, 23 and 24. These tie members are provided as shown in Figures I and III, 80 and are adapted to extend between the uprights and to assist in keeping the same properly spaced. By referring to Figure II, it will be noted that these tie members cross and extend beyond the outer margin of the 85 uprights. This crossing is affected by slotting each cross tie as shown at 20. This is also shown in Figure I. The crossing of these tie members together with the square corners of the uprights, forms a socket 26 90 which socket is adapted to receive a pin 27 secured upon the lower extremity of the next above upright. In securing the second set of uprights upon the top of the first set, it will be noted that the braces of the second 95 set are extended so as to be secured to the upper ends of the first set of uprights, thus tying the second unit to the first unit. This construction is carried out throughout the remainder of the structure. At 28 I have 100 shown brackets secured to the sides of the uprights at a point substantially midway of their length. These brackets are adapted to receive a staging plank 29 thereon. The staging plank is removable therefrom and is 105 held to the uprights by strap iron plates 31 as is best shown in Figures I and IV. These strap iron plates are adapted to pass over

eye bolts 32 and a pin 33 is inserted to prevent accidental slippage. These staging planks are adapted to be moved upwardly as the silo progresses in height. If the space 5 between these brackets 28 is too great, the plank may be first moved from one set of brackets to the extending ends of the tie members which will serve the same purpose as the brackets 28. It will thus be seen that 10 I have devised an extremely simple structure which may be extended or lengthened to suit all requirements ordinarily met in the construction of silos, and at the same time take up very little room during transportation or storage.

It is to be understood that the form of my invention herewith shown and described is to be taken as a preferred example of the same, and that various changes in the shape, 20 size and arrangement of parts may be resorted to without departing from the spirit of the invention or the scope of the subjoined claim.

Having thus described my invention, I claim:—

In a staging, a plurality of uprights supports spaced apart one from the other, extensible cross braces secured between adjacent uprights, extensible tie members adapted to rest on said uprights and having 30 their extremities extend beyond said uprights, said extremities being adapted to support staging planks and brackets mounted on said uprights at a point substantially midway of their length, said tie members 35 and said uprights each being adapted to receive therebetween a depending pin, said pin being secured upon an upright and adapted to rest upon the top of said first mentioned uprights, cross braces secured between said second mentioned uprights and said first mentioned uprights, substantially 40 as and for the purpose described.

In testimony whereof I affix my signature.

LAURENCE A. PETERSEN.
